UNITED STATES PATENT OFFICE.

WILLIAM R. KINNEAR, OF NEW CASTLE, PENNSYLVANIA.

METAL-SHEET-SEPARATING MACHINE.

1,130,983.

Specification of Letters Patent.

Patented Mar. 9, 1915.

Application filed September 22, 1910. Serial No. 583,300.

To all whom it may concern:

Be it known that I, WILLIAM R. KINNEAR, a citizen of the United States, and whose residence and post-office address is New Castle, 5 in the county of Lawrence, State of Pennsylvania, have invented certain new Improvements in Metal-Sheet-Separating Machines, of which the following is a specification.

10 This invention relates to a machine for automatically separating sheets of metal which have been caused to adhere by some step or steps in the process of their manufacture, as for instance, by the annealing process. Such a machine is described and broadly claimed in my previous application, Serial #518196, filed September 17th, 1909, according to which the group or pack of adhering sheets is introduced into the machine 15 and subjected to the lifting action of a sucker or suckers at a point or points where adhesion has not taken place or has been preliminarily destroyed, after which a knife or knives are caused to enter beneath the 20 lifted portion of the sheet and, while supported with some freedom of accommodating itself to the plane of separation, is forced between the first and second adhering sheets in a manner to force separation; 25 the front edge of the knife being beveled and extending at an incline to the direction of the knife's movement, so that it acts as a shearing wedge in enforcing separation, and the sheet being suitably withdrawn from the 30 machine when separation is complete.

The object of the present invention is to add to a machine of the kind above described, certain elements or devices which coöperate with the general features referred 40 to in a manner to make the operation more complete and more uniformly successful even under the greatest difficulties encountered in practice; also to embody the general principles and broad features of the 45 previously filed application in a machine of simplified construction.

To the last named end, one feature of the present invention consists in employing but a single knife for the separation of the 50 sheets; this knife being divided from front to rear into a pair of blades so that while adapted to simultaneously enter beneath separately raised corners and separate opposite ends of one and the same sheet, should 55 two sheets be lifted at one end and but a single sheet at the other end, the second

sheet which is partially above one blade of the knife and partially below the other blade will not be destroyed as would be the case if but one continuous blade were employed, but the two partially separated sheets will merely remain in position until the knife again withdraws and the operation is repeated and both blades finally enter beneath the top sheet alone, to completely separate it and permit it to be withdrawn from the machine.

A further feature consists in providing means whereby sheets that may become prematurely severed are prevented from leaving the pile except as they are individually separated and released by the knife, such means preferably comprising a stop or stops, normally in the path of the sheets, but depressed by each stroke of the knife just 75 sufficiently to release the topmost sheet above the knife, while barring the escape of those below.

A further feature consists in means whereby, after separation by the knife is 80 commenced, the starting edge of the sheet will be gripped and the sheet thereby firmly held against buckling or folding under the friction of the knife during separation; said means preferably comprising gripping jaws 85 thrown in at the proper time, and means such as suction lifts, (which may receive their lifting tendency simultaneously with the initial devices, but through resilient connections) which suction lifts will raise the 90 intermediate portion of the sheet, within reach of the gripper.

Another feature consists in an automatically actuated gripping device which enters upon and holds the pile of sheets beneath 95 the one being separated, immediately after the separating operation has commenced.

A further feature consists in providing means whereby the separating knife, after completing the separation of the sheet, will 100 abut against the edge of the sheet and move it in the direction of delivery until it is picked up by discharging means, such as a pair of feed rolls or the like, the means on the knife for embodying this delivery movement to the sheet being in the form of a yielding pusher which affords ample resistance to move a detached sheet, but will itself yield to the abnormal resistance of a sheet that still adheres, so as to avoid injury 110 either to the sheet or to the machine.

A further feature consists in providing a

supporting bed for the pile of sheets, (preferably embodied in a truck by which the pile may be conveyed to and positioned in the machine) with justifying means which enables 5 force lateral and angular shifting of the pile, as the pile diminishes, by the removal of sheets, in case the pile, as a whole, is distorted. That is to say the pile may constantly yield to lateral clamps, as the pile 10 lowers to keep the top portion thereof in normal position, or adjusted in relation to the devices (lifter, grippers, stops, knife, and delivery means) which act upon particular portions of the sheet; such shifting 15 being facilitated by mounting the upper part of the bed upon the lower part through the medium of ball bearings or the like. Manually operated shifting means are provided for moving the bed in one lateral direction; movement of the truck upon its wheels affords shifting in the other lateral direction, and rotation of the bed affords angular adjustment.

Further features of the present invention 20 relate to details of construction of the several parts, which together with the broad features above outlined will be hereinafter fully described, and particularly pointed out in the claims.

25 In the accompanying drawings; Figure 1 is a plan view of a complete machine embodying the several features of my present invention in illustrative form. Fig. 2 is a vertical longitudinal section of the line 2—2, Fig. 1, with the lower part of the machine left out. Fig. 3 is a front view of the machine. Figs. 4 and 5 are detail views at right angles to each other of the means for holding down the remaining sheets in the 30 pack after separation of the top sheet has commenced. Figs. 6 and 7 are views at right angles to each other of the means for holding the front edge of the top sheet after separation has commenced. Fig. 8 is a detail view of one of the stops which normally projects above the rear edges of the sheets, to prevent them sliding forward under the friction of the knife, but which are depressed by the knife when separation is 35 complete, in order to permit the separated sheet alone, being delivered to the discharge means. Fig. 9 is a perspective view of the stop shown in Fig. 8. Fig. 10 is a view of one of the suckers. Figs. 11 to 14 different 40 views of the supporting truck.

45 1 represents the frame of the machine, which is formed on its inner vertical face with guide tracks to receive the knife carrier 2 which may be constructed in the form 50 of a U shape rim, adapted to slide horizontally in the frame.

55 3 represents the two-part or divided knife which is mounted in the rim 2 and which is adapted to be reciprocated through means of 60 the arms 4, the pitman 5 and the cranks 6

which latter are mounted upon stub shafts 7^a extending from the main shaft 7, which is rotated by means of motor driven gear wheels 7^b 7^c.

The knife is divided as at 8, by a central 70 space, to receive a sheet one end of which may have been lifted above one blade or end of the knife while its other end remains beneath the other blade or end of the knife. This space 8 however is not so wide in proportion 75 to the thickness of the knives as would permit the intermediate portion of the top sheet continuing to adhere to the next sheet below while the ends thereto are separated; that is to say, the blades of the 80 divided knife effect the separation by wedge action of the forward edges thereof, while the sheet being separated is forced to remain in a plane parallel with and close upon the knife, so that with a given thickness of the 85 knife and some stiffness of the sheet ample space can be left between the two blades of the knife to avoid shearing a sheet which is below one blade and above the other, and still bring the intermediate part of the sheet 90 under the separating influence of the blades or knife members when both ends of the sheet are above the same.

In my previous application Serial No. 518,196 claiming a machine of this type as 95 well as in my application Serial No. 563,211 filed May 24, 1910 and claiming the process carried out by said machine, reference is made to the serration, inclination or indentation of the forward edge or edges of the 100 knife or knives for purpose briefly stated, of developing shearing wedging action and prevent buckling or folding of the sheets; the inclined wedging edge, while extending 105 forwardly and outwardly, being terminated near either on the side of the sheet and the remaining forward portion of the knife being formed of a rearwardly and outwardly inclined edge. Instead of two opposed 110 knives, each having the main inclined edge 115 extending entirely across the knife as in the previous application, each blade in the present case has a main inclined edge 9 extending rearwardly and inwardly to the intermediate separation of the blades together with a short rearwardly and outwardly extending edge 10. This form of knife embodies the advantages described in the 120 previous applications referred to, together with still further advantages consisting in the dishing or curving of the sheet between the two advance corners of the blades, which naturally stiffens the sheet longitudinally of the machine and therefore makes the buckling or folding of the sheet 125 less liable to occur.

11 represents the suction lifts for the corners of the sheets substantially as described in the process application which are raised by means of the arms 12 fulcrumed in 130

rear of the main shaft 7 and acted upon at suitable intervals by cams on said shaft, while 13 represents the holddown device which depresses the edges outside of said lifts for the purpose of preventing more than one sheet being raised at a time, as also described in my previous application.

In the more difficult class of work to be performed by a machine of this kind, especially where sheets have been over heated in annealing, adhesion has become much stronger and folding or buckling of the sheets is more likely to occur. As a safeguard against this, I now employ an additional lifter or lifters 14, acting upon intermediate portions of the front edge of the top sheet, in such a manner that as soon as separation is sufficiently advanced the front edge will be raised against upper jaw 15 so that the gripping jaw 16, pivoted at 17, may be forced in beneath the sheet and caused to formally grip it, by means of the pitman 18 working in the cam 19 on the main shaft 7 (see particularly Figs. 6 and 7). Cam 19 is merely suggestive of a suitable mechanical device for imparting movement to the gripping jaw 16, and is constructed so that the gripping movement takes place each time the knife 3 advances sufficiently beneath the top sheet to insure separation of the front edge of said sheet. The lifters 14 may be conveniently raised and lowered through the medium of the beam 20 which is supported from the lifting arms 12 of the lifts 11. But in order that the suction of the lifts 11 may not be destroyed by upward pull before the points formed by the edges 9 and 10 of the knife have had time to enter beneath the front portion of the sheet raised by the lifts 11, the lifts 14 are raised by the beam 20 through the medium of the springs 21 confined between the beam and shoulder 22 on the air pipe 23 of each lift. This permits the lifts 14 to yield to the resistance offered by the sheet upon which their flexible suction ends 14^a are pressed, until the knife has separated a sufficient portion of the sheet, after which the compression stored in the springs 21 will be sufficient to lift the front edge of the sheet where attacked by the lifts 14, and permit the gripping jaw 16 to enter. The front edge of the sheet will therefor during the raising procedure take the shape of two waves, the crests of which start beneath lifts 14 and move in an inward direction until joining on the center line of the machine. Inasmuch as the entry of the gripping jaw is timed by the same shaft 7 which controls the movement of the knives 3, separation of the sheet and consequent lifting of the edge will necessarily take place in time to admit the gripper.

In order to positively press the suckers 14^a upon the sheet which it is to lift, pipe

23 is surrounded by pipe 24 confined between the beam 20 and the head of the sucker 14^a and in order to limit the upward movement of the sucker 14^a, its head is confined beneath the limiting stops 25 on the lower bearing of the head.

In order to grip the remaining sheets of the pack until separation of the top sheet is completed, jaw 26, mounted to slide in downwardly inclined bracket 27, and provided with an over-hanging lip 28, is moved by an arm 29 on a rock shaft 30, forward into gripping position, each time the top sheet is lifted and separation is started.

To start the delivery of the sheet from the machine as soon as separation is complete, the knife carrier 2 is provided with a yielding pusher 31 mounted on a lifting incline 32 which brings the edge of the sheet into the path of the pusher; said pusher being sustained by the compression spring 33 with sufficient pressure to start the delivery of a completely separated sheet, but being permitted by said spring to yield under the resistance of an adhering or partially separated sheet until the knife reverses its movement. This means, that the upper part of the pusher 31 will yield if two sheets happen to be pushing against it at the same time, while on the other hand, the pusher would remain upright, as shown in Fig. 2 if only one sheet is pushing against it after having been raised by the wedges or inclines 32. The spring resistance should consequently be slightly above that caused by the friction from the weight of a single loose sheet. The resistance of an adhering or partially separated second sheet would of course be many times, probably hundreds of times greater, so that the spring adjustment would be quite easy and could have very wide range.

In order to prevent the top sheets or several adhering sheets, separated from the rest of the pile, moving forward in advance of the knife, stops 34 are provided at suitable intervals just beyond the far edges of sheets, at the delivery end of the machine. As will be seen from Figs. 8 and 9, these stops comprise an arresting face 35 against which the sheets abut and laterally presented bevel face 36 in position to be encountered by the inclined forward edge 9 of the blade, whereby the stop will be depressed when the knife reaches it and when separation is necessarily complete and the sheet freed for delivery; the stop being returned by spring 37 when the knife is withdrawn, so that it again bars the escape of the sheets. To complete delivery of the sheets, any suitable means, as for instance a pair of rolls 38, may be provided where the sheet will be forced between them, during the last part of the forward movement of the knife, through the medium of the yielding pusher 31.

Beyond the jaw 15 and carrying said jaw 130

is a presser bar 39 which rests upon the top of the pile until the knife begins to enter, and thereat presses the top sheet down upon the knife in a manner to greatly assist in holding the sheet against buckling or folding. Above the center of the sheet is a presser foot 40 which rests upon the pile and supports the machine when the knife is withdrawn and while the side clamps are released to limit the downward movement of the machine the thickness of one sheet. Actuated by suitable connections from the main shaft 7 such as cams or eccentrics, the holding down device 13, the presser bars 39 and the presser foot 40 are all timed to be lifted sufficiently to allow the knife to pass under the top sheet, this lifting taking place on the advance of the knife and subsequent to the clamping of the pile in the frame 1, and the clamping of the frame to posts 50 as described hereafter. In order to adjust the top of the pile relatively to the lifting sucker, the grippers, the knife, and the stops, the bed of the machine not shown in the assembled views comprises a lower supporting plate 41, and an upper plate 42 resting thereon through the medium of an intermediate plate 41^a carrying the balls 42^a or other antifriction means. This permits the plate upon which the pile rests to move both laterally and relatively or angularly. A pivot pin 41^b is provided on the base, which pin fits within the bearing 41^c in the top plate 42. The bed plate 41 is preferably mounted upon wheels thus forming a truck, which wheels 41^r may run upon a track so that the truck may be removed from the machine and rolled to a distant point to receive the pile, and then returned to introduce the pile within the machine. The wheels thus permit accurate positioning or lateral adjustment of the pile of sheets in the machine. To permit adjustment of the pile in another direction, the lower plate 41 carries a post 43 that projects upward through a slot 44 in the upper plate and is threaded to receive an adjusting screw 45, whose outer end is squared for the reception of a key while its inner end is rotatably fixed in the lower plate. Adjusting means 43, 44, 45, is so applied that it does not restrict automatic angular or rotary movement of the upper bed plate. With the described method of supporting bed, each time the side clamps 46 are pressed against the upper portion of the pile, by the toggle levers 47, which at one end are held by stationary lugs on the frame the machine is clamped to the pile by means of said clamps 46 and the sustaining bar 48 on the opposite side of the pile. By this clamping, the pile adjusts itself to bring its upper portion in normal position relatively to the working parts of the machine.

The present machine is preferably supported by two pairs of posts 49 and 50, as

in my previously filed application referred to which are threaded to enable the frame 1 to be raised when a new pile of plates is put in and the pitch of the threads of these posts, which receive the nuts on the frame of 70 the machine, is such that the machine will settle by gravity until arrested by the presser bars 39 and presser foot 40, each time the clamps are released. It will therefore be evident that the frame 1 will be alternately 75 suspended on the posts 50 and on the presser bars 39 and presser foot 40.

To permit arresting of the machine without undue pressure of the clamps which might otherwise upset the edges of the sheet, 80 I have provided a brake-beam 51, carrying shoes 52 bearing against the posts 50. Said brake-beam is connected by draw-rods 53 with such parts of the toggles 47 as will cause the brake shoes 52 to be applied to the 85 posts and thus arrest the downward tendency of the machine, each time the clamps are applied to adjust the pile, and previous to raising the presser foot 40 to admit the knife. Rods 53 impart their pull to the 90 brake beam 51 through the medium of springs 54, the tension of which may be adjusted at will by the nuts 55.

The toggle levers are actuated by inclined grooves, or cams 2^b, see Fig. 2, situated in 95 the sides of the knife carrier 2, which advance with the knife, thus straightening out the toggle, pressing the clamp 46 against the pile and clamps 52 against the posts 50.

I claim:—

1. In a machine for separating adhering sheets of metal, a separating slide comprising two blades having a space between them, the edge of each blade being broken to form a forwardly protruding point.

100

2. In a machine for separating adhering sheets of metal, a separating slide comprising two blades, having a space between them extending in the direction of the separation movement, the edge of each blade being 110 broken to form a forwardly protruding point.

105

3. In a machine for separating adhering sheets of metal, a separating slide comprising two blades having a space between them 115 extending longitudinally to the separation movement, along the middle line of the slide, the edge of each blade being broken to form a forwardly protruding point.

4. In a machine for separating adhering 120 sheets of metal, a separating slide comprising two similar blades symmetrically disposed and spaced apart on opposite sides of the middle longitudinal line of the slide, the edge of each blade being broken to form a 125 forwardly protruding point.

5. In a machine for separating adhering sheets of metal, a separating slide comprising two similar blades symmetrically disposed and spaced apart on opposite sides of 130

- the middle longitudinal line of the slide and having receding forward edges, the edge of each blade being broken to form a forwardly protruding point.
6. In a machine for separating adhering sheets of metal, a separating slide comprising two similar blades symmetrically disposed and spaced apart on opposite sides of the middle longitudinal line of the slide, and having forward edges inclined rearwardly and inwardly toward the middle line of separation, the edge of each blade being broken to form a forwardly protruding point.
7. In a machine for separating adhering sheets of metal, a knife comprising two similar blades symmetrically disposed and spaced apart on opposite sides of the middle longitudinal line of the knife and having forward edges inclined rearwardly and inwardly toward the middle line of separation from forward points located within the sides of the knife and also from said forward points, toward the sides of the knife, said forward edges being beveled on their upper side to form wedges.
8. In a machine for separating adhering sheets of metal, a knife comprising two similar blades symmetrically disposed and spaced apart on opposite sides of the middle longitudinal line of the knife and having forward edges inclined rearwardly and inwardly toward the middle line of separation from forward points located near but within the sides of the knife and also from said forward points, toward the sides of the knife, said forward edges being beveled on their upper side to form wedges.
9. In a machine for separating adhering sheets of metal, a reciprocating knife comprising two similar blades symmetrically disposed and spaced apart on opposite sides of the middle longitudinal line of the knife and having forward edges inclined rearwardly and inwardly toward the middle line of separation from forward points located near but within the sides of the knife and also from said forward point, toward the sides of the knife, said forward edges being beveled on their upper side to form wedges and means for simultaneously raising the corners of a sheet that are adjacent to said forward points to admit such blades beneath it on the forward movement of said knife.
10. In a machine for separating adhering metal sheets a separating knife, means for forcing it beneath the sheet to be separated and means carried by the knife, engaging the edge of the sheet after separation is complete and imparting movement to the sheet in the direction of delivery.
11. In a machine for separating adhering metal sheets, a separating knife, means for forcing it beneath the sheet to be separated, and a yielding pusher carried by the knife,
- engaging the edge of the sheet after separation is complete and imparting movement to the sheet in the direction of delivery, but yielding under abnormal resistance of the sheet.
12. In a machine for separating adhering sheets of metal, means for initially raising the corners of a sheet, separating blades entering beneath the raised corners and thereafter encompassing separation of the whole sheet, and a yielding pusher carried by the knife, encountering the sheet at completion of separation, and imparting movement thereto in the direction of delivery, but yielding under abnormal resistance of the sheet.
13. In a machine for separating adhering sheets of metal, means for raising adjacent corners, a knife comprising two blades separated on opposite sides of a middle line and adapted to enter beneath the raised corners, means forcing the knife beneath the sheet and a yielding pusher carried by the knife in the plane of separation between the blades.
14. In a machine for separating adhering sheets of metal, a separating knife, means for initially raising a portion of the sheet to admit the knife, and additional sheet raising means acting upon a portion of the sheet separated by the knife.
15. In a machine for separating adhering sheets of metal, a separating knife, means for initially raising a portion of the sheet for admitting the knife, additional sheet raising means acting upon a portion of the sheet separated by the knife, and grippers gripping the last named raised portion of the sheet.
16. In a machine for separating adhering sheets of metal, a separating knife, means for initially separating a portion of the sheet to admit the knife, beneath it and means gripping and holding the edge of the sheet during separation.
17. In a machine for separating adhering sheets of metal, a separating knife, means for initially separating a portion of the sheet to admit the knife beneath it, and means gripping and holding the edge of the sheet during separation, comprising lifting means acting upon a portion of the sheet separated by the knife and a gripping device engaging the portion so raised.
18. In a machine for separating adhering sheets of metal, a separating knife, means for initially separating a portion of the sheet to admit the knife beneath it, and means gripping and holding the edge of the sheet during separation, which consists of a fixed jaw, means for raising the edge of the sheet against said fixed jaw, and a movable jaw moving beneath and against the sheet to grip it against the fixed jaw.
19. In a machine for separating adhering

sheets of metal, a separating knife, means gripping and holding the edge of the sheet, where separation commences, during the separating operation of the knife, and means 5 confining the sheet immediately above the separating knife.

20. In a machine for separating adhering sheets of metal, a separating knife, hold down plates for pressing the sheet against the knife, and means for gripping the edge of the sheet at which separation commences, comprising an extension of a hold-down plate, and a gripping jaw entering beneath the sheet and gripping it against the extension of the hold-down plate.

21. In a machine for separating adhering sheets of metal, a separating knife, hold-down bar adopted to rest upon the top of the pile of sheets, means for raising the hold-down bar to permit the knife to pass beneath the uppermost sheet, and means carried by the hold-down bar for gripping the edge of the sheet where separation begins, and holding the same during the separating 25 operation of the knife.

22. In a machine for separating metal sheets, a separating knife, means for raising a portion of the sheet to admit the separating knife, means for raising an intermediate portion of the sheet, and an actuating 30 connection for both said raising means.

23. In a machine for separating sheets of metal, a separating knife, suction means for raising a corner of the sheet to admit the 35 knife beneath it, a suction means for raising an intermediate portion of the sheet, an elevating connection for lifting the suction means first named, and an elastic connection between said elevating connections second 40 named suction means.

24. In a machine for separating metal sheets, hold-down bars adapted to press upon the uppermost sheet, grippers, for the edge of the sheet, carried by the hold-down bars, 45 suction lifts to raise the edge of the sheet, also carried by said hold-down bars.

25. In a machine for separating metal sheets, hold-down bars, adapted to press upon the uppermost sheet, grippers for the 50 edge of the sheet, carried by the hold-down bars, suction lifts to raise the edge of the sheet, also carried by said hold-down bars, including limiting means for restricting the upward movement of the lifts.

26. In a machine for separating metal sheets, a separating knife, suction means and gripping members for initially raising a portion of the sheet to admit the knife, and a sliding hold-down entering beneath 55 the knife and gripping the pile of sheets beneath the knife as separation takes place.

27. In a machine for separating metal sheets, a separating knife, suction means and gripping members for initially raising a portion of the sheet to admit the knife and 65 a hold-down entering beneath the knife and gripping the pile of sheets beneath the knife as separation takes place, comprising inwardly and outwardly sliding jaws and inclined guides for said jaws.

28. In a machine for separating metal sheets, posts upon which the machine is guided, and brake shoes adapted to press against said posts to arrest the downward movement of the machine before separation 75 takes place.

29. In a machine for separating metal sheets, posts upon which said machine is guided, a presser foot adapted to rest upon the pile of sheets to limit the downward 80 movement of the machine and clamps adapted to embrace the pile of sheets in order to adjust the pile before each separation and brake shoes carried by the machine, adapted to press against the posts to arrest the downward movement; said brake shoes having connection with the clamps whereby the 85 brakes are applied by the movement of the clamps.

30. In a sheet separating machine, clamps 90 adapted to embrace the pile of sheets at each separating stroke and adapted to adjust the pile relatively to the devices which operate thereon.

31. In a sheet separating machine a bed 95 for supporting a pile of sheets to be separated comprising a lower bed plate and an upper bed plate angularly movable thereon whereby the bed has freedom of adjustment and clamps adapted to embrace the pile of 100 sheets at each separating stroke and adapted to adjust the pile relatively to the device which operate thereon.

32. In a sheet separating machine a bed for supporting a pile of sheets to be separated comprising a lower bed plate and an upper bed plate angularly movable thereon whereby the bed has freedom of adjustment and clamps adapted to embrace the pile of sheets at each separating stroke 110 and adapted to adjust the pile relatively to the device which operate thereon; said bed having positive means for laterally adjusting the upper bed-plate on the lower one.

The foregoing specification signed at New 115 York, N. Y., this 27th day of June, 1910.

WILLIAM R. KINNEAR.

In presence of two witnesses:—

RAYMOND H. TRUMAN,
M. L. SULLIVAN.
